UNITED STATES PATENT OFFICE.

NICHOLAS S. KEY, OF CHICAGO, ILLINOIS.

ATTACHMENT FOR RAILROAD-SWITCHES.

1,187,997.

Specification of Letters Patent. Patented June 20, 1916.

Application filed March 20, 1915. Serial No. 15,795.

To all whom it may concern:

Be it known that I, NICHOLAS S. KEY, a citizen of the United States, residing at Chicago, in the county of Cook and State of Illinois, have invented certain new and useful Improvements in Attachments for Railroad-Switches; and I do hereby declare the following to be a full, clear, and exact description of the invention, such as will enable others skilled in the art to which it appertains to make and use the same.

This invention relates to new and useful improvements in attachments for railroad switches, and has for its principal object to provide a safety appliance which may be easily and quickly applied to railroad switches of the ordinary construction without in any way altering the same.

Another object of the invention is to provide a device which will effectively bind switch points to rails, thus removing danger of the switch "splitting" and derailing trains or cars.

A further object of the invention is to provide a binding device for the switch points which may be secured either to the rails or to the ties at the desire of the user, and which will firmly force the respective switch points into engagement with each respective rail.

Still another object of the invention is to provide a device which when in place will effectively hold the rails against spreading.

A still further object of the invention is to provide a novel means for holding the attachment in place on the rails, which may be easily and quickly removed at the desire of the user.

In order to accomplish the above objects, there is employed a pair of bearings which may be either secured to the rails or to the ties at a suitable point near the free ends of the switch points. A suitable rocker shaft is rotatable in the bearings and carries at each end a compression lug. Carried by the switch points are suitable filler strips which are provided with offset portions which are connected to the strips by cam faces, and against these filler strips the compression lugs bear in holding the switch points firmly in engagement with the rails. The rocker shaft may be controlled by a lever, or may be operated from the switch operating mechanism, but it is essential that the shaft be turned so as to swing the lugs downwardly before the switch can be thrown. After the

switch is thrown, the rocker shaft is rotated so that the lugs are again turned upwardly and engage either of the offset portions of the filler strips, thus firmly locking the switch points to the rails. The switch point opposite the one which engages the rail when the switch is thrown in either position, is separated from its respective rail by the lugs, and it will be evident that even though the said switch points should become separated from the switch rod, the same could not return to position against the rail as the lug will effectively form a stop, thus leaving a passage for the reception of the wheel flange of the rolling stock.

In order to gain a clear and exact knowledge of the device designed for the above purposes, reference will be had to the following specification and accompanying drawings wherein like numerals refer to like parts and in which,

Figure 1 is a top plan view of a switch showing the same in "clear" position and showing this improved safety appliance in operative position thereon, Fig. 2 is an enlarged sectional view taken on line 2-2 of Fig. 1, Fig. 3 is an enlarged sectional view on the line 3-3 of Fig. 1, Fig. 4 is a detail perspective view showing the brackets for supporting the rocker shaft to the rails, Fig. 5 is a detail perspective view of one of the compression lugs, Fig. 6 is an enlarged sectional view through a rail and rail plate showing the plates on which the switch points ride, Fig. 7 is a longitudinal sectional view through the connector by which the switch points are operatively connected, Fig. 8 is an enlarged fragmentary view of one of the switch points constructed in accordance with the modified form of the device, Fig. 9 is a sectional view taken on line 9-9 of Fig. 8, and Fig. 10 is a detail perspective view of the filler strip.

Referring to the drawings by characters of reference, the numeral 1 designates a railroad rail of the usual construction. This rail 1 is generally known as the stock rail against which the switch points 2 operate. Connecting the switch points 2 is a suitable switch rod 3 which is provided intermediate its ends with the sleeves 4 having the enlargements 5 formed at one end. These enlargements are bent upwardly as at 6 and are apertured to receive the bolts 7 which extend through the switch points and through the extensions 6 to form

a connection between the switch points and the switch rod 3. This switch rod 3 may be operated in any suitable manner which is not shown. The switch points are slideable 5 on the offset portions 8 of the tie plates 9 on which the rails 1 are mounted, and each of these switch points carries a suitable filler strip designated generally by the numeral 10, which will be more fully hereinafter described.

10 The filler strip 10 above referred to, comprises the body 11 provided at one end with the offset portion 12 which is arranged to overlie the portions 6 of the extensions 5, 15 and at the opposite end of this body 11 is the thickened portion 13 provided with the face 14, which is connected with the face of the body 11 by means of the cam face 15. The opposite face of the thickened portion 20 is inclined as at 16 and the body 11 is extended and bent to form the hook 17 which engages around the end of the switch point.

25 The construction thus far described, is used in connection with both forms of my improved safety appliance, and it is against the face 14 of the filler strip 10 that the compression lug, which will be more fully hereinafter described, and which is carried 30 by the rocker shaft, bears.

35 The rocker shaft above mentioned, is rotatably mounted in suitable brackets carried by either the rail or the ties, which brackets will be described in detail hereinafter, and the rocker shaft is designated by the numeral 18. This rocker shaft has secured intermediate its ends the compression lugs, designated generally by the numeral 19, each of which comprises the sleeve 20, having 40 formed thereon the upstanding portion 21 provided with the arcuate outer face 22, which arcuate face engages the face 14 of the filler strip 10 when the device is in operation. The ends of the rocker shaft 18 are preferably threaded as at 23 and provided with the reduced extensions 24 which are arranged to project into the bore 25 formed in the socket 26, which in turn is formed on the rod 27, the end of which is bent angularly as at 28 to form a lever. 50 This angular portion 28 is provided with the slot 29 for the reception of a suitable staple or eye carried by the plate 30 which is secured to one of the ties.

55 In order to support the rocker shaft 18 in operative position on the rails, there is provided the attaching member 31 comprising the base 32 which engages beneath the base of the rail and on which is formed the 60 flange engaging member 33. This flange engaging member terminates in the web engaging portion 34 and the base 32 is formed at one end with the downwardly extending transverse enlargement 35 which is formed 65 with the longitudinal aperture 36, in which

the ends of the shaft 18 are journaled. A suitable downwardly extending enlargement 37 is formed near the opposite end of the base 32 and is provided with the aperture 38 for the reception of the shank 39 of the hook bolt designated generally by the numeral 40. One end of the shank is threaded as at 41 and the opposite end of said shank is upturned as at 42 to form a hook, the inner face 43 of which engages the rail flange. 75 A suitable nut 44 is threaded on the threaded end 41 of the bolt, and it will be evident that when the device is in place, the base 32 extends beneath the base of the rail, while the flange engaging portion 33 and web engaging portion 34 engage the flange and web of the rail respectively. The hook overlies the opposite rail flange, and the shank thereof extends through the opening 38 in the enlargement 37, thus firmly holding the 80 whole in place.

85 In event it is desired to use the modified form of the support illustrated in Figs. 8 and 9, there is provided the plate 45 which is provided with suitable fastening-receiving apertures for the reception of a fastening means by which the device is secured to a pair of ties. This plate 45 bridges the space between the ties and has riveted or otherwise secured to its under surface the 90 plate 46, provided with the downward extension 47 having formed therein the longitudinally extending aperture 48 in which the ends of the rocker shaft are journaled. It will thus be seen that the only material 95 difference between the structure illustrated in Fig. 1 and that illustrated in Fig. 8, is the fact that the method of supporting the shaft is somewhat modified.

100 It will be evident from the foregoing that in use, assuming the left hand rail to be designated by the character A, and the right hand rail to be designated by the character B, the said rail A is continued and bent outwardly to form the stock rail for the main 105 track and for the switch or spur. The rail B continues in a straight line and forms a continuation of the main track. The switch point *a* is arranged to engage the bent portion of the stock rail A as illustrated in Fig. 1 to form a left hand continuation of the main track, while the switch point *b* is arranged to engage the rail B to cooperate with the bent portion of the rail A in forming a track for the spur or switch. Assuming that the switch is to be set for "clear", it will be evident that the switch point *a* engages the stock rail A and when the rocker shaft is turned into the position shown in Fig. 1, it will be evident that the compression lug *a'* engages the filler strip carried by the switch point *a*, while the compression lug *b'* extends upwardly between the switch point *b* and rail B. When it is desired to 110 set the switch for the spur or siding, the 115

handle 28 is swung upwardly, thereby releasing the engagement of the lug a' with the switch point a and also turning the lug b' downwardly so that it cannot engage the switch point b and the switch is then shifted. The lever 28 is then turned into the position illustrated in Fig. 1, and it will be evident that the compression lug b' will engage the filler strip carried by the switch point b and thus firmly press the same against the rail B, while the lug a' will extend upwardly between the switch point a and the rail A. In this way it will be evident that a safety appliance is provided which will effectively prevent the switch from "splitting" and derailing the rolling stock when rolling thereover. It will thus be seen that a device is provided which will effect a material saving in both life and property and many of the accidents due to open switches will be eliminated.

While in the foregoing there has been shown and described the preferred embodiment of this invention, it is to be understood that such changes may be made in the combination and arrangement of parts as will fall within the spirit and scope of the invention as claimed.

What is claimed is:

30 1. In combination with a railroad switch having a pair of switch points and rails adapted to be engaged by the switch points, filler members secured to the inside of the switch points, cam faces on the filler members, said cam faces being disposed in-

wardly, a shaft journaled beneath the rails and at a point adjacent the ends of the switch points, lugs on the shaft and curved cam faces on the lugs, said curved cam faces on the lugs being adapted to engage the cam faces on the filler members so that upon rotation of the shaft the cam faces will engage and the filler members will be moved toward the rails through the curvature of the cam faces on the lugs. 45

2. In combination with a railroad switch provided with a pair of spaced rails and a pair of switch points, said switch points being adapted to be shifted simultaneously, of filler strips, each of said filler strips comprising a body, an enlarged portion at one end of the body, a cam face on the outer face of the enlarged portion, the inner face of the enlarged portion of the body being in the same plane, a hook at the extreme end of the enlarged portion to engage the end of the switch point on which the same is used, a shaft rotatable beneath the rails adjacent the ends of the switch point and cam lugs on the shaft arranged to engage the cam faces when the switch points are against the rails whereby upon rotation of the shaft the switch points will be forced against the rails. 55 60

In testimony whereof I affix my signature in presence of two witnesses.
